UNITED STATES PATENT OFFICE.

HENRY HALLECK BURTON, OF LOS ANGELES, CALIFORNIA.

ADDING ATTACHMENT FOR TYPE-WRITERS.

No. 931,358.

Specification of Letters Patent.

Patented May 11, 1909.

Application filed July 23, 1908. Serial No. 444,932.

To all whom it may concern:

Be it known that I, HENRY HALLECK BURTON, a citizen of the United States, and a resident of Los Angeles, in the county of Los Angeles and State of California, have invented a new and Improved Adding Attachment for Type-Writers, of which the following is a full, clear, and exact description.

This invention relates to certain improvements in adding attachments for typewriters, and more particularly to that type of attachment disclosed in my prior patent Number 883,081, granted March 24, 1908.

The object of my invention is to improve certain of the details of my previous device referred to, while maintaining substantially the same general arrangement of parts and method of operation.

More in detail, the more important objects of my invention are as follows: to facilitate the attachment and detachment of the adding device to and from the numeral key-bars of the typewriter; to provide for the adjustment of the device in respect to the numeral key-bars, whereby any numeral wheel may be rotated to different extents by the operation of different key-bars and these amounts accurately determined and controlled; to improve the numeral wheels, whereby the numerals may be printed on a larger scale and rendered more clearly visible; to provide certain improvements in the carrying devices, by means of which one numeral wheel is rotated one point upon the rotation of an adjacent wheel through ten points, and to improve the numeral wheel-rotating means, whereby the rotation of the wheels is insured and slipping prevented.

Other objects will be hereinafter set forth in connection with the detail description of the construction.

It is evident that various details of my improved construction may be employed in adding devices of other types than that illustrated.

Reference is to be had to the accompanying drawings, forming a part of this specification, in which similar characters of reference indicate corresponding parts in all the figures, and in which—

Figure 1 is a vertical section through a portion of a typewriter having my improved adding attachment secured thereto; Fig. 2 is a front elevation of the parts shown in Fig. 1, the key-bars being shown in section; Fig. 3 is a front elevation showing the parts with-

in the casing of my improved device, the front of the casing being removed; Fig. 4 is a detail view similar to a portion of Fig. 1, but on an enlarged scale; Fig. 5 is an inverted plan view of the parts shown in Fig. 4; Fig. 6 is a top plan view of the outer end of the wheel-rotating arm shown in Figs. 4 and 5; Fig. 7 is a detail showing the mechanism employed for adjusting the operating arms in respect to the main shaft, a portion thereof being shown in section; Fig. 8 is a top plan view of the parts shown in Fig. 7; Fig. 9 is a detail showing an auxiliary key employed for releasing the numeral wheel-carrying casing; and Fig. 10 is a detail showing one of the depending carrying levers.

The typewriter which I have illustrated as being provided with my improved adding attachment, is substantially the same as that shown in my prior patent above referred to. This typewriter includes a main frame 1, a roller 2, a carriage 3, a plurality of key-bars 4, and keys 5. Within the frame of the typewriter, there is mounted the main frame 6 of my improved device, and movable within said main frame 6, is a casing 7 carrying the numeral wheels and the operating mechanism therefor. The frame 6 constitutes a guide and support for the casing 7, and mechanism is provided whereby the casing moves longitudinally of the frame simultaneously with the movement of the carriage.

Within the frame of the typewriter and beneath the casing of the adding device, (see Figs. 1 and 2) there is mounted a rock shaft 8, substantially the same as that disclosed in my previous patent. Extending outwardly from this rock shaft, there are provided a plurality of arms 9, each of which is connected at its front end to one of the key-bars. In my previous patent, this means includes a band encircling the key-bar and a spring connecting the band with the end of the arm 9, but in my present and improved construction, the spring is omitted, although a band 10 is employed. The band is clamped to the key-bar in any suitable manner and terminates in an upwardly-extending hook or lug 11. Depending from the front end of each arm 9 is a bar 12, the lower end of which comes adjacent the lug or hook 11 when the key-bar is in its highest position. The bar 12, upon its rear side, carries a lug 13, to which is pivoted a catch or hook 14, adapted to engage with the lug or catch 11 carried by the key-bar. The catch or hook 14 is formed

substantially the same as a bell crank lever, and is provided with an outwardly-extending arm or branch 15, normally pressed downward by the action of a small leaf spring 15^a. 5 This spring tends to keep the hooks or catches 14 and 11 in engagement with each other, so that a downward movement of the type bar causes a simultaneous movement of the corresponding arm 9. For detaching the several catches 14, so that the typewriter may be operated independently of the adding attachment, I provide a rock shaft 16, having its opposite ends mounted in the typewriter frame. The shaft is provided with a plurality of arms 16^a, which when the rock shaft is rotated, may be brought beneath the arms 15 to raise the latter against the action of the springs 15^a and hold the catches 14 out of engagement with the catches 11. The shaft 20 may be rotated by means of a hand wheel 17 at one end thereof, and is provided with a coil spring 17^a, which normally tends to rotate it in one direction. For holding the shaft stationary and against the action of the spring, said shaft is preferably provided with a small ratchet wheel 17^b, which engages with a pivoted dog 17^c. With the parts in the position indicated in Fig. 1, the adding attachment is operated by the operation of 25 the typewriter, but by rotating the shaft 16 counterclockwise to raise the arms 15, the dog 17^c holds the shaft against return rotation and the typewriter may be operated independently of the adding device. Instead 30 of holding the arms 9 in their raised position by springs attached to the front ends thereof, I provide a plurality of springs 9^a, each attached to a rod 9^b disposed below and back of the rock shaft 8. The upper end of each 35 spring is connected to a small ring or eye 9^c upon the rear side of the hub of the corresponding arm.

In the construction shown in my previous patent, I provide the hub of each of the arms 40 9 with different sized slots therein, for engagement by corresponding pins in the rock shaft 8, but this necessitates the provision of a plurality of different kinds of arms 9 and renders difficult the adjustment of the arms 45 should they or their holding pins 8^a become worn. To avoid this, I, in my present construction, provide the hubs of all of the arms 9 with elongated slots of the same length, as 50 shown particularly in Figs. 7 and 8; and provide the rock shaft with a plurality of pins 8^a extending through these slots. Secured to the upper side of each arm 9, is an adjusting bar 9^d, having one end thereof adjacent the hub of the arm and having a slot therein 55 through which the corresponding pin 8^a also extends. Each bar adjacent its forward end, is threaded and extends through a lug 9^e on the same arm, the adjacent bar being normally held against longitudinal movement 60 by nuts 9^b engaging with opposite sides of

the lugs 9^e. By adjusting the nuts 9^b, the rod or bar 9^d may be moved longitudinally in respect to any arm 9, and the rock shaft may be caused to rotate when the arm has been swung through any desired angle. By 70 so constructing the parts, all of the arms 9 may be made alike and interchangeable.

Extending rearwardly from the rock shaft 8, as shown particularly in Fig. 1; there is provided a lever 18 connected at its rear end to a vertically-extending link 19, which latter at its upper end is connected to a lever 20 intermediate the ends of the latter. This lever is pivoted at its rear end to a rearwardly-extending bracket 21, and at its forward end is 80 constructed for operating the numeral-wheel rotating means. The parts 18, 19, 20 and 21, are substantially the same as shown in my previous patent, save the forward or operating end of the lever 20. 85

As shown particularly in Figs. 3 to 6, inclusive, the casing 7 serves to support a main shaft 22, upon which are rotatably mounted a plurality of numeral wheels 23. The casing also serves to support the wheel-rotating mechanism, locking mechanism, carrying mechanism and the zero setting mechanism, all of which are similar in many particulars to the corresponding mechanism shown in my previous patent. Each wheel 23 is free to rotate on the shaft, and is provided with a continuous row of teeth 24, an intermediate row of teeth 25, and a plurality of ratchet teeth 26 in between the two rows of teeth 24 and 25, and one face of each wheel is provided with a row of laterally-extending teeth 27. The row of teeth 24, as previously stated, is continuous, and the number of teeth is preferably a multiple of ten. The teeth 25 are of substantially the same size as 90 the teeth 24, but are arranged in series of sevens, each series being spaced from the next one by a gap, the width of three consecutive teeth. Thus, the number of series of sevens in the teeth 25 is equal to one-tenth 95 the number of teeth in the row 24. The ratchet teeth 26 may be any desired distance apart, as they do not serve in the counting or in determining the extent of rotation; preferably, they correspond in number and location to the teeth 24. There are one-tenth as 100 many teeth 27 as there are teeth 24, and each tooth 27 comes opposite to a gap in the row 25. 105

Instead of printing the numerals on the 110 numeral wheels 23 about the periphery thereof, I provide a separate wheel 23^a, having a toothed portion 24^a adapted to intermesh with the teeth 24 of the corresponding wheel 23 and having a larger portion 23^b provided with a smooth periphery, upon which the numerals are printed, only one numeral being visible at a time through a corresponding window in the casing 7, as indicated in 115 Figs. 2 and 4. Although the wheels 23, 120

themselves do not bear the numerals, yet the rotation of the wheels 23 directly causes a change in the numerals to be visible through the windows or openings in the casing, and I therefore hereinafter refer to the wheels 23 as the "numeral wheels", and the wheels 23^a as the "indicating wheels".

For causing intermittent rotation of each wheel through one space upon the rotation 10 of the next adjacent wheel of lower denomination through ten spaces, I provide a carrying mechanism differing very materially from that shown in my previous patent. In my present construction I provide a plurality of depending arms 28, corresponding to the several numeral wheels, and each suspended from a rod 28^a above the shaft 22. Each rod is suspended directly above the corresponding wheel, but adjacent the upper 20 edge of the wheel it is offset as indicated in Fig. 10 and extends downwardly to adjacent the lower edge of the wheel. A portion of the rod is curved to partially encircle the shaft 22. Each rod at its lower end carries 25 an outwardly-extending lug 28^b, lying in the path of the teeth 27 of the next adjacent wheel, and each rod is limited against swinging movement in one direction by a stop 28^c, and is normally held against said stop by a 30 suitable coil spring 28^d. Adjacent the offset portion, each rod is provided with a dog or pawl 29, (see Fig. 10); having its lower end in engagement with the ratchet teeth 26 of a corresponding wheel. As the numeral 35 wheel rotates through ten spaces, a tooth 27 of said wheel engages with the lug 28^b of the rod 28 of the next adjacent wheel of higher denomination, and swings said rod toward the front of the casing. At the instant that 40 a zero on the corresponding indicating wheel comes to view, the lug 28^b slips beneath the tooth 27 and the spring 28^d draws the rod back to the position indicated in Fig. 4. The return movement of the rod causes a 45 rotation of the wheel 23 corresponding to said rod, through one space. Thus, each time a numeral wheel rotates through ten spaces, the adjacent numeral wheel of higher denomination is rotated through one space.

50 For rotating a numeral wheel upon the operation of a numeral key of the typewriter, there are provided a plurality of arms 30, corresponding to the arms employed in my previous construction. Each of these 55 arms carries a roller 30^a at its free end, which is adapted to engage within a yoke 20^a of the lever 20. Each arm 30 is provided adjacent the periphery of its corresponding wheel 23, with a pawl 31 adapted to engage with the 60 ratchet teeth 26, the pawl being held continuously in engagement with said teeth by a suitable spring 31^a secured to the arm and engaging with the upper end of the pawl. As the arm is raised, the wheel 23 remains 65 stationary, but upon the descent of the arm,

the wheel is rotated to an extent dependent upon the elevation to which the arm was raised. Each wheel is normally locked against rotation, but the upward movement of any arm serves to unlock the wheel and 70 permit of its being rotated upon the descent of the arm. This locking mechanism is also adapted to be operated when the adjacent wheel of lower denomination has been rotated through ten spaces. I thus provide a 75 single locking mechanism in place of the two separate locking mechanisms illustrated in my previous patent.

Below the wheels 23 and in the rear thereof, I mount a rod 32, having a plurality of 80 collars 33 thereon, corresponding to the number of wheels. Each collar is provided with a slot therein, into which extends a pin 34 of the rod, so that the collar has a limited rotation in respect to the rod. Each of these 85 collars is provided with three outwardly-extending arms, one of which, 35, terminates in an upwardly-extending hook end 36, adapted to engage in the teeth 24 and constitute a locking member. A second of these 90 arms, 37, extends into the path of the teeth 27 of the next adjacent wheel of lower denomination, so that during the rotation of one wheel 23, it will intermittently rotate one collar 33 and lower the arm 35 to unlock 95 the adjacent wheel of higher denomination at the instant that another one of the teeth 27 releases the rod 28 and permits its return movement to rotate said wheel of higher denomination. The third arm, 38, carried by 100 the collar 33 extends rearwardly and is in the form of a spring. This arm extends beneath a stud 30^b carried by the arm 30 at the end thereof, so that when the arm 30 is in its lowermost position, it depresses the spring 105 arm 38 and rotates the sleeve 33 to hold the arm 35 in locking position. The instant that the arm 30 is raised, the corresponding collar may rotate and unlock the wheel to permit its rotation during the return movement of the arm 30. Thus, all of the wheels 110 are normally locked, but the raising of any arm 30 unlocks the corresponding wheel, and the rotation of any wheel brings a zero to view through the window of the casing, unlocks the wheel of higher denomination and rotates it one space. For preventing the rotation of the wheels 23 in the reverse direction during the raising of the arms corresponding thereto, I provide a plurality of 115 dogs 39, pivoted to a transverse rod 40 mounted in the casing 7. This rod preferably also serves to support one end of each of the springs 28^d, which hold the rods 28 in one of their limiting positions.

In connection with the mechanism above described, I employ zero-setting mechanism substantially the same as that illustrated in my previous patent, save that the shaft 45 instead of being mounted above the wheels 130

23, is mounted below the same. Upon the shaft are mounted the pinions 46, which upon the longitudinal movement of the shaft, may be brought into mesh with the intermediate 5 series of teeth 25. The shaft 46 is provided with a suitable milled head or wheel 48 at its end, and a spring 49 for normally holding the shaft in such a position that the pinions do not engage with the wheels 23.

10 The casing 7, as previously stated, is mounted to slide within the frame 6, and for moving it in one direction, I provide a third spring 54 of substantially the same character as that commonly employed in connection 15 with typewriter carriages. I employ substantially the same escapement for releasing the casing 7 a step at a time upon the movement of the typewriter carriage, and permitting its movement simultaneously with 20 the carriage and in the same direction, as is disclosed in my previous patent. The detail description of such mechanism is not thought to be necessary in this application. For holding the casing 7 at the left-hand end of 25 the frame 6 and locking it against return movement, I preferably provide a pivoted catch 50 (see Fig. 2), adapted to engage with a pin or stop 51 on the casing 7, and having its opposite end connected to a link 52, (see 30 Fig. 9), which extends downwardly to an auxiliary key-bar 53. This key-bar is pivotally mounted upon the shaft 8 and is provided at its forward end with a striking plate 55. The key-bar is normally held in its 35 raised position by the action of a spring 56, similar to the springs 9^a of the arms 9.

Having thus described my invention, I claim as new and desire to secure by Letters Patent:

40 1. In combination with a typewriter having a plurality of numeral keys, a shaft, arms mounted thereon and movable relatively thereto, means connecting said arms to their corresponding keys, and independent means 45 for adjusting the relative movement of said arms in respect to said shaft.

2. In combination, a rock shaft, a plurality of arms mounted thereon, means for moving said arms to rock said shaft, and an 50 adjusting bar carried by each of said arms and substantially parallel thereto, for controlling the movement of said arms in respect to said shaft.

3. In combination, a rock shaft, a plurality of arms mounted thereon, a plurality of pins carried by said shaft adjacent said arms, and an adjusting rod carried by each of 55 said arms and movable longitudinally thereof, and having a slot therein for receiving the 60 corresponding pin of said shaft.

4. In combination, a rock shaft, a plurality of pins carried thereby, a plurality of arms mounted on said shaft and each having a slot therein for receiving the corresponding pin, a rod carried by said arm and

having a slot therein for receiving the corresponding pin, a lug on said arm and through which said rod extends, and nuts threaded upon said rod and adapted to engage with opposite sides of said lug.

70

5. In combination with a typewriter having a plurality of numeral key-bars, a catch or hook carried by each of said bars, a rock shaft, a plurality of arms mounted thereon, a depending rod carried by each of said arms, 75 and a hook carried by each of said depending rods and adapted for engagement with the hook of the corresponding numeral key-bar.

6. In combination with a typewriter having a plurality of numeral key-bars, a hook 80 carried by each of said key-bars, a rock shaft, a plurality of pivoted hooks supported by said arms and adapted to engage with said first-mentioned hooks, and rotatable means for holding each of said second-mentioned 85 hooks out of engagement with said first-mentioned hooks.

7. In combination with a typewriter having a plurality of numeral key-bars, a hook or catch carried by each of said bars, a member adjacent each of said key-bars, a hook pivoted to each of said members and adapted to engage with the hook of the corresponding key-bar, a shaft, and a plurality of arms extending outwardly therefrom and adapted upon the rotation of said shaft to hold said second-mentioned hooks out of engagement with said first-mentioned hooks.

90

8. In combination with a typewriter having a plurality of numeral key-bars, a hook 100 or catch carried by each of said bars, a member adjacent each of said key-bars, a hook pivoted to each of said members and adapted to engage with the hook of the corresponding key-bar, a shaft, a plurality of arms extending outwardly therefrom and adapted upon the rotation of said shaft to hold said second-mentioned hooks out of engagement with said first-mentioned hooks, means normally tending to rotate said shaft in one direction, and means normally preventing said rotation.

105

9. In an adding machine, a shaft, a plurality of wheels loosely mounted thereon, an arm pivoted to said shaft adjacent each of said wheels and each adapted to swing in one direction to rotate the corresponding wheel and to swing in the reverse direction independently of said wheel, a rock shaft adjacent said wheels, and a plurality of locking 115 arms carried thereby for engagement with said wheels, and means whereby any one of said arms is moved to inoperative position upon the movement of the corresponding first-mentioned arm away from one of its two 120 limiting positions.

115

10. In an adding machine, a shaft, a wheel mounted thereon, an arm pivoted to the wheel adjacent the shaft and having a pawl for engagement with said wheel to rotate 130

125

- the latter when said arm is moved in one direction, a second shaft adjacent the periphery of said wheel and having a collar thereon, an arm carried by said collar and adapted to engage with said wheel to lock the latter against rotation, and a second arm carried by said shaft and adapted to engage with said first-mentioned pivoted arm, whereby the latter when in one position, holds said locking arm in operative position.
11. An adding machine, comprising a plurality of wheels, each having a row of laterally-extending teeth, means for rotating each of said wheels a definite distance upon the movement of an adjacent wheel through a distance ten times as great, said means including a plurality of pivoted rods having engagement with said laterally-extending teeth, means for normally locking said wheels against rotation, and means including an arm extending into the path of said laterally-extending teeth for intermittently unlocking each of said wheels to permit its rotation by said pivoted rod.
12. An adding machine, including a plurality of wheels, a lever arm adjacent each of said wheels and adapted to rotate the same, a shaft adjacent said wheels and having a plurality of collars thereon, a locking arm carried by each of said collars for engagement with the corresponding wheel to hold the latter against rotation, an arm carried by each of said collars for engagement with the corresponding lever arm to unlock the wheel upon the movement of said lever arm, and a second lever arm carried by each of said collars and adapted to engage with an adjacent wheel to unlock its corresponding wheel intermittently during the rotation of said adjacent wheel.
13. In an adding machine, a plurality of

wheels, each having a row of laterally-extending teeth and a row of radially-extending teeth, means adapted to be intermittently operated by said laterally-extending teeth for rotating the next adjacent wheel, and a plurality of oscillatory collars adjacent said wheels and each having an arm for engagement with the radially-extending teeth of its corresponding wheel, to lock said wheel, and having an arm extending into engagement with the laterally-extending teeth of an adjacent wheel to be operated by the latter for intermittently unlocking its corresponding wheel.

14. An adding machine, comprising a shaft, a plurality of wheels mounted thereon, a lever arm adjacent each of said wheels and adapted to rotate the same, each of said arms terminating in a roller, and a pivoted lever having a yoke adapted to engage with any one of said rollers and serving to operate any one of said levers.

15. An adding machine, comprising a plurality of wheels, a lever arm adjacent each wheel and adapted to engage with its corresponding wheel for rotating the latter, all of said wheels together with their corresponding arms being movable axially of the wheels, each of said lever arms terminating in a roller, and a lever mounted on a stationary pivot and terminating in a yoke adapted to engage with said rollers in succession when said wheels are moved axially.

In testimony whereof I have signed my name to this specification in the presence of two subscribing witnesses.

HENRY HALLECK BURTON.
